UNITED STATES PATENT OFFICE.

GEORGE HOWARD GOULD, OF WEST LEBANON, ASSIGNOR TO HIMSELF, AND
CHARLES KING GOULD, OF READFIELD DEPOT, MAINE.

WINDOW-SCREEN.

SPECIFICATION forming part of Letters Patent No. 387,781, dated August 14, 1888.

Application filed September 22, 1887. Serial No. 250,417. (No model.)

To all whom it may concern:

Be it known that I, GEORGE HOWARD GOULD, of West Lebanon, in the county of York and State of Maine, have invented new and useful 5 Improvements in Window-Screens, of which the following is a full, clear, and exact description.

My invention relates to window screens, and has for its object to provide a simple, inexpensive, and efficient screen, which may be quickly applied to or removed from a window-frame, and is adapted to fit windows of different widths and heights.

The invention consists in certain novel features of construction and combinations of 15 parts of the window-screen, all as hereinafter described and claimed.

Reference is to be had to the accompanying drawings, forming a part of the specification, 20 in which similar letters of reference indicate corresponding parts in all the figures.

Figure 1 is an inside face view of a window-frame with my improved window-screen applied thereto and partly broken away and in 25 section. Fig. 2 is a plan view with the window-frame and guide-strips in horizontal section on the line αx , Fig. 1. Fig. 3 is a plan view of the frame of the screen with its fastenings or clamp-plates removed, and Fig. 4 is an 30 enlarged plan view of one of the clamp-plates.

The window - screen is made with a main frame, A, the opening of which is closed by screen-cloth, B, applied in any approved way, and the frame may be strengthened and ornamented also by applying angular metal cover- 35 plates to it, so as to overlap or overlie the corners of the screen-cloth. At each side the frame A is provided with a rabbet, a' , leaving a tongue, a , of considerable width, which is 40 adapted to lap onto the inner face of a guide-strip, C, which is broader or wider than window-screen guide-strips usually are, and is fixed in any approved way to the window-frame W, and may be made of metal or any 45 other suitable material.

The screen-frame A is held with its opposite side tongues, $a a'$, flat to the guide-strips C C on the window-frame by means of clamp-plates D, applied one at each corner of the screen- 50 frame and at the top and bottom edges of the

frame. These clamps D are made alike, and consist of a metal or, it may be, a hard wood plate having at one end an open slot, d , edged with an elastic or rubber facing, E, at its three sides, and the clamp is provided at its inner portion with a long slot, d' , through which fastening screws or bolts F are passed into holes f , made in the screen-frame. The elastic, yielding, or rubber facing E snugly fits the opposing faces of the guide-strip C, which fills 55 the clamp slot d when the screen is in operative position, and the friction of the clamp-facings E on the guide-strips C is sufficient to hold the window-screen at any place to which it may be adjusted along the window-frame 60 without further fastenings of any kind.

It is obvious that the broad guide-strips C C and the deep rabbets and wide tongues of the window-screen frame will allow the screen to be readily fitted to window-frames of varying 65 widths, and that when the screen tongues $a a'$ are placed against the guides C C and the screws F are loosened the clamp-plates D may be slid on the screen-frame, so as to snugly fit their facings E onto the guides, whereupon the 70 screens will be tightened to hold the screen-frame in position. When the screen is to be removed from the window, it is only necessary to loosen the screws F and slip the clamp-plates 75 D inward clear of the guides C, whereupon the 80 screen may be lifted inward from the window-frame.

There is nothing in the construction and operation of the clamp-plates D to prevent their use when the screen-frame has outer tongues, 85 a^2 , besides the inner tongues, a , or when the opposite sides of the frame are simply grooved instead of rabbeted from the back, as will be understood from the full and dotted lines at the right-hand side of Fig. 3 of the drawings; 90 but the rabbeted construction providing inside tongues, a , only is preferred, as the screen so made may be more easily applied to and removed from the window-frames.

Should the screen be too short to fill the 95 opening in the window-frame made by fully raising the lower window-sash, I have provided an auxiliary bottom bar or plate, G, which is rabbeted or grooved at the ends to fit the guides C, like the screen-frame A, and is preferably 100

provided with dowels g , fitting holes in the screen-frame, and should the screen be too long, so that its upper bar, a^3 , would be at a higher level than the lower rail of the raised lower sash, I provide for closing the opening which then would be left between the screen-cloth and the sash-rail by means of an upper auxiliary cross bar or plate, H , which is fitted to slide upon dowel-pins $h h$, fixed to the screen-bar a^3 , and may be adjusted higher or lower within the screen-frame and close to the screen-cloth to safely overlap the bottom rail of the raised lower window-sash, as will readily be understood.

15 It is obvious that the screen-frame A may be provided with two tongues, aa^2 , at one side and an inner tongue, a , only at the other side without departing from the spirit of my invention.

Having thus fully described my invention, 20 what I claim as new, and desire to secure by Letters Patent, is—

1. The combination, in a window-screen, of a frame provided with screen-cloth and fitted to guides on the window-frame, and clamp-25 plates fitted to the screen and provided with elastic facings having frictional contact with the guides, substantially as described, for the purpose set forth.

2. The combination, in a window-screen, of 30 a frame, A, provided with screen-cloth, B, and

clamp-plates D, provided with open-ended slots d , having elastic or yielding facings E, adapted to guides on the window-frame, and provided also with slots d , and screws or bolts F, passed through the clamp-slots d into the screen-frame, 35 substantially as herein set forth.

3. The herein - described window - screen clamp, consisting of a plate, D, having an open-ended slot, d , provided with an elastic or yielding facing, E, and provided also with a slot, d' , 40 adapted to receive fastenings to hold the clamp to the screen-frame, substantially as herein set forth.

4. The combination, with a window-screen frame, of guides h , fitted to the top rail of the 45 frame and projecting downward about parallel with the screen-cloth, and a bar or plate, H , fitted on the guides h and against the screen-cloth and made about the same thickness as the screen-frame, substantially as shown and 50 described, whereby, should the top bar of the screen-frame be too high to fit against the lower rail of the raised window-sash, the bar H may be adjusted within the screen - frame to fit against said sash-rail, as and for the purpose 55 set forth.

GEORGE HOWARD GOULD.
